UNITED STATES PATENT OFFICE.

YUKITOSHI SAKAKURA, OF SHIBUYAMACHI, TOYOTAMAGUN, TOKYO-FU, JAPAN.

PROCESS FOR MANUFACTURING INCANDESCENT LAMPS.

Application filed June 1, 1927, Serial No. 195,815, and in Japan April 6, 1927.

My invention relates to a process for manufacturing an incandescent lamp, and has for its object to render the manufacture of incandescent lamps simple and economical.

5 In the known art of manufacturing the incandescent lamp the lamp bulb is first formed by blowing molten glass in a mould then cut off the blow pipe and cooled. The lamp contents with the filament on the frame 10 is then placed in the bulb and sealed up thereto by the application of heat. The bulb is afterward exhausted of air and fitted with the base to form an incandescent lamp.

15 According to the present invention the lamp contents properly put together are previously held within the blow pipe. After the bulb has been formed the lamp contents are immediately forwarded into the bulb and are sealed thereto while hot. Then the bulb 20 is cut off the blow pipe to form an electric lamp. Thus the formation of bulb and the sealing of the contents may be successively performed before the bulb is cooled and the 25 operation is rendered more easy and economical. In the manufacture of those incandescent lamps filled with inert gases, the bulb after having been formed and sealed with the lamp contents, is exhausted of the air contained therein and filled with the inert 30 gas as usual. Whereas, according to the present invention the manufacture of the gas filled lamps may be immediately completed by blowing the bulb with the desired inert gas itself whereby further economy of labour 35 and cost may be obtained.

The invention is more particularly explained with reference to the accompanying drawing in which

Fig. 1 is a longitudinal sectional view of the lamp bulb as formed in the mould.

Fig. 2 is a similar view as the lamp contents are placed in the bulb.

Fig. 3 is an elevation of the bulb as completed and cut off the blow pipe.

Fig. 4 is a cross sectional view of the blow pipe.

In carrying out the invention in practice the lamp contents viz the filament and lead wires properly placed on the frame are held 50 in the blow pipe so that they can be moved forward. A preferable form of the blow

pipe is shown. The pipe (1) is provided inside with a clip (2) the stem (4) of which is passed through a longitudinal slot (3) formed at the side of the pipe (1). A sleeve 55 (5) provided with a handle (6) is slidably fitted on the pipe (1) and the stem (4) of the clip (2) is fixed thereto. The sleeve (5) is provided with packing rings (7) (7) at its ends to prevent the leakage of blowing air. 60

The clip (2) is arranged in the pipe (1) to hold the lamp contents put together in a suitable form, an example of which is shown. A glass tube or stem (8) is provided with wire arms (9) on which a spiral filament (10) 65 is helically carried and connected at both ends to lead in wires (11) (11). A glass ring (12) is placed on the stem (8) and leading wires (11) (11) to hold them in the position. Said stem (8), arms (9), filament (10) and leading wires (11) are previously brought together to form the lamp contents and the upper end of the stem (8) and the leading wires (11) (11) are held at the clip (2). Then the sleeve (5) is pulled upward 75 by the handle (6) on the pipe (1) and the lamp contents are kept quite inside the pipe (1), as shown in Fig. 1.

A suitable quantity of molten glass is taken at the end of the pipe (1) and it is blown 80 in the mould (13) by the human breath or by a suitable mechanical means to form a lamp bulb (14) as in the known art. After the bulb (14) has been formed the sleeve (5) is immediately pulled downward by the handle (6) on the pipe (1) and the lamp contents with the filament (10) is forwarded to the desired position in the bulb (14), as shown in Fig. 2.

The bulb (14) is pressed at its neck (15) 90 while hot so that the stem (8) and the leading wires (11) (11) are hermetically sealed thereto. Then the bulb (14) is cut off the pipe (1) and the glass body of the incandescent lamp is made as shown in Fig. 3. 95 For the lamp to be exhausted through the glass tube (8) as shown, the tube (8) is preferably provided at its bore with a slender metal tube (16) or the like to prevent the collapse of the glass tube against the sealing 100 pressure of the neck (15).

Having now particularly described and as-

certained the nature of my said invention and in what manner the same is to be performed I declare that what I claim is:—

An improved process for manufacturing an incandescent lamp characterized that the filament, its supports and lead in means, properly brought together to form the lamp contents, are sildably held within the blow pipe

and after the lamp bulb has been blown the lamp contents are forwarded into the bulb ¹⁰ just formed and are immediately sealed thereto, substantially as described.

In testimony whereof I have affixed my signature.

YUKITOSHI SAKAKURA.
